LIQUID DISPENSING APPLICATOR

Joseph Greskovicz, Chicago, Ill.

Application August 21, 1935, Serial No. 37,193

4 Claims. (Cl. 91—67.4)

This invention relates to improvements in applicators for dispensing liquid from containers. More particularly, my invention provides an inexpensive cap for a glass jar or other container such as those in which pharmaceutical and medicinal products are packaged and sold in the market, which container-closing cap means is combined with dispensing and applying means for the liquid contents, the container being used as a handle. The principal utility of my invention is for a structure for applying pharmaceutical or medicinal products such as liniment, alcohol, and others which are usually applied externally to the skin, which products must necessarily and desirably be deposited and applied to the skin surface in limited and substantially evenly distributed quantity, or, in the case of certain products, to be rubbed into the skin or other absorbing surface. While the foregoing sets forth the principal uses, I desire that it be understood that my device may also serve as a regulatory self-feeding device for the application of various liquids and for various purposes.

It is an object of my invention to provide a combined container-closure cap and restricted nozzle which are preferably formed integrally and the interiors of which communicate with each other and wherein the nozzle terminates in a restricted slotted opening which is normally obstructed by a block of porous material which permits restricted flow of liquid therethrough.

A further object of my invention is the provision of a combined screw threaded container-closure cap and communicating outlet nozzle which terminates in a relatively long but narrow opening which opening is positioned substantially diametrically with reference to the container cap and which has removable, yieldable, porous and renewable means disposed over said opening to restrict and evenly distribute the out-flowing liquid, in combination with a removable hood or cap which frictionally and releasably engages the outer portions of the nozzle per se.

A further object of my invention is the provision of a combined metal cap and nozzle having a relatively long narrow nozzle opening and having integrally formed opposed flanges above and adjacent said opening adapted to releasably hold a block or section of porous fibrous material which is adapted to restrict and evenly distribute the outflowing liquid.

Other and further objects of my invention will be apparent from the following description and claims.

This invention, in (a preferred form), is illus-

trated and described in the following specification and claims.

Fig. 1 is a perspective view of my nozzle liquid applicator with the metal hood shown in raised position.

Fig. 2 is a top plane view showing the liquid applicator and nozzle opening from above.

Fig. 3 is a cross sectional view of my liquid applicator taken on line 3—3 of Fig. 2.

Fig. 4 is an elevational view of the disk or sealing ring which is insertable into the closure cap of my invention for effecting proper seal.

Referring to the drawing, reference numeral 10 indicates a container or jar of glass or other suitable material such as is used in the packaging of pharmaceutical or medicinal products. Said container 10, while illustrated in the preferred form of the drawing as circular in cross section, may be of any other known shape and size within a limit for convenient handling and gripping by a person's hand. Reference numeral 11 indicates an annular metal cap which in shape and size is substantially like screw type caps of conventional construction, said cap 11 having perpendicularly and downwardly extending annular flange 12 which is suitably spirally grooved to form screw thread 13, as clearly shown in the cross sectional drawing of Fig. 3, said screw threaded flange 12 being adapted to threadingly engage corresponding external threads formed adjacent the upper periphery of the jar or container 10.

Screw cap 12 has a relatively large central aperture 14 formed therein which forms an outlet port for the container liquid contents when the container is tilted or inverted. A sealing ring 15 of cardboard or other fibrous moisture-impervious material is preferably inserted to fit snugly in screw cap 12 in order that said screw cap will form a liquid tight seal on the container 10, said sealing ring 15 setting on the upper periphery of the container and being impinged therebetween and said screw cap. As indicated in Fig. 3, after the purchaser of the applicator and contents purchases same and desires to apply the liquid contents such as liniment or the like, he may either perforate the sealing ring 15 along perforated circular area as indicated by reference numeral 15a to form an aperture in register with aperture 14, or said sealing ring may be entirely removed and the screw cap and applicator device reassembled.

Securely mounted on the upper surface of screw cap 12 is a metal nozzle 16 which although shown of rectangular shape, may assume various shapes, widths or lengths. In the preferred form nozzle 15

16 is preferably formed from a single metal blank which is suitably slit and bent to form a substantially rectangular box-like structure as clearly shown in Figs. 1 and 3 and wherein the upper 5 portion of the relatively longer opposite sides 17 and 18 respectively are bent along a horizontal line and diagonally toward each other until they are relatively near each other to form a relatively narrow elongated opening 19 as clearly indicated 10 at the top of Fig. 3. The edges of the shorter end members are secured by welding or the like to adjacent edges of nozzle's side walls 17 and 18. When the converged sides of the opposite walls 17 and 18 have been formed to leave relatively narrow 15 opening 19, each of said sides is bent at an obtuse angle and outwardly from each other and the ends thereof are thence bent toward each other to form oppositely facing spaced apart concave flanges 20 and 21 respectively, the upper 20 edges of said flanges terminating a short distance apart along their entire length as clearly indicated in Fig. 1.

A section or block of cotton or wool felt 22 (which may also be of other pervious fibrous material) is inserted between opposite flanges 20 and 21 wherein said felt block 22 is impinged but removable. Said felt block 22 extends from one end of said flanges 20 and 21 to the other end and acts to partially obstruct and regulate the 30 flow of liquid through nozzle opening 19. It is apparent that upon tilting or inversion of the applicator, that the liquid contents will contact and soak into felt block 22 and be thereby substantially evenly distributed along the entire width 35 of opening 19 and felt block 22 and also be regulated to an even flow so that the proper and desired amount of liquid will have been applied. It is to be noted that a portion of the felt block 22, because of its yieldable and spongy body, extends above flanges 20 and 21, this providing 40 means whereby the inverted applicator and particularly the felt block 22 may be rubbed along the surface to which the liquid is to be applied resulting in relatively thin application of the liquid 45 contents.

As important uses of the applicator are designed in the field of manual application of medicinal and pharmaceutical products wherein maintenance of cleanliness is important, I have 50 provided a substantially rectangular and cubical hood or cover 23 of relatively thin metal, as shown in Fig. 1. The size of the cover 23 is such that it will snugly fit about the 4 sides of the nozzle 16 to thereby enclose the felt block 22 and maintain 55 it free from exposure to air and dust.

I am aware that numerous details of the construction of my invention may be varied through a wide range without departing from the principles of my invention, and I therefore do not desire to limit my patent to the particular or preferred form illustrated.

I claim as my invention:

1. A dispensing applicator for a liquid container comprising a main cap body adapted to be releasably secured over the mouth of a container, a portion of said cap body extending about and encircling a portion of the sides of said container;

a tubular nozzle on said cap body having two of its opposite walls converging together to form a relatively narrow opening extending diametrically with respect to said cap body, said cap body having an aperture therein to form a communication from the interior thereof to the interior of said tubular nozzle; a block of porous fibrous material disposed upon said narrow nozzle opening, and flanges formed integrally with said converged nozzle walls adapted to removably hold said fibrous material therein. 5

2. A dispensing applicator for a liquid container comprising a main cap body adapted to be releasably secured over the mouth of a container, a portion of the sides of said container; a substantially rectangular upwardly extending tubular nozzle secured on said cap body, said cap body having a central aperture to form an outlet port to interior of said nozzle, two of the opposite walls of said nozzle extending first vertically and then converging diametrically toward each other to form a relatively narrow opening and thence at the point of said opening each being bent diametrically and away from each other and the upper edges of said sides being bent toward each other to form a relatively narrow elongated chamber, and a block of relatively narrow yieldable and expansible fibrous liquid absorbent material removably mounted in said nozzle chamber and upon said nozzle opening. 25

3. A dispensing applicator adapted to be mounted on a liquid container comprising a metal cap having downwardly extending portions thereof for engaging the sides of the container and having an upper central opening therein, an upwardly extending nozzle formed integrally with said cap and having diametrically opposite walls thereof curved toward each other to form an elongated relatively narrow opening, the upper end of said diametrically opposite walls being thence bent upwardly and concave to present oppositely facing concave surfaces immediately above said elongated narrow opening; and a porous liquid absorbent fibrous body removably disposed between said concave portions of said nozzle walls, said body acting to obstruct and restrict outflow of liquid through said nozzle. 45

4. A dispensing applicator adapted to be mounted on a liquid container comprising a metal cap having downwardly extending portions thereof for engaging the sides of the container and having an upper central opening therein; an angular sealing ring in said cap, the lower surface of which is adapted to rest on a container periphery; an upwardly extending nozzle formed integrally with said cap and having diametrically opposite walls thereof curved toward each other to form an elongated relatively narrow opening, the upper end of said diametrically opposite walls being thence bent upwardly and concave to present oppositely facing concave surfaces immediately above said elongated narrow opening; and a porous liquid absorbent fibrous body removably disposed between said concave portions of said nozzle walls, said body acting to obstruct and restrict outflow of liquid through said nozzle. 55

JOSEPH GRESKOVICZ.
